UNITED STATES PATENT OFFICE

WILLIAM J. MILLER, OF SWISSVALE, PENNSYLVANIA, ASSIGNOR TO HARTFORD-EMPIRE COMPANY, OF HARTFORD, CONNECTICUT, A CORPORATION OF DELAWARE

CAM STRUCTURE

Original application filed May 27, 1928, Serial No. 111,957. Divided and this application filed August 15, 1928. Serial No. 299,732.

This application for Letters Patent is a division of an application for Letters Patent Serial Number 111,957 filed by me in the United States Patent Office on May 27th, 5 1926, now Patent Number 1,738,499.

My present invention, while more particularly designed and intended for use in mechanism for feeding molten glass to fabricating machines, may be advantageously 10 employed in other arts wherein cam-drives are employed.

A characteristic feature of my present invention is a new and improved cam structure which provides for adjustment for varying and regulating the cam-action.

Other novel features of construction and arrangement of parts will appear from the following description.

In the accompanying drawings, wherein 20 I have illustrated a practical embodiment of the principles of my invention, Fig. 1 is a face view of the cam structure.

Fig. 2 is a sectional view of the same taken along the line 2—2 in Fig. 1.

25 Fig. 3 is a sectional view taken along the line 3—3 in Fig. 2.

Fig. 4 is a diametric section of one of the hub members of the cam structure.

Referring to the drawings, 63 represents 30 a driven shaft upon which the cam-structure is mounted and with which the cam-structure rotates. The cam structure is substantially as follows.

For convenience of assemblage and disassembly, the hub of the cam is formed of two parts, the front hub-part 65 and the rear hub-part 66, said parts being fixed to the shaft 63 as by the pins 67.

40 The rear hub-part is radially split so that its perimetral surface may be expanded, as will be more fully described.

The rear hub-part 66 has a differential exterior perimetral surface, the surface of greater diameter 68 being at the rear and that 45 of less diameter 69 toward the front, the radial shoulder 70 separating the two perimetral surfaces.

Likewise the front hub-part 65 has a differential exterior perimetral surface, the surface of larger diameter 71 being at the front 50

and that of lesser diameter 72 at the rear, a shoulder 73 separating said perimetral surfaces. The diameter of the surface 72 of the front hub-part is somewhat less than that of the surface 69 of the rear hub-part so that a 55 shoulder 74 is formed where the hub-parts abut against each other.

The cam-carrier 75 is a ring which is provided with a differential bore, the portion of greater diameter 76 being at the rear and 60 slipping over the perimetral surface 69 of the rear hub-part 66 when the latter is not expanded, and abutting against the shoulder 70. The front portion 77 of the bore of the cam carrier 75 surrounds the perimetral surface 72 of the front hub-part. In assembling the cam-structure, the rear hub-part is first mounted on the shaft and fixed thereto, the cam-carrier is then slipped in place, and then the front hub-part is slipped into place and 70 fixed on the shaft 63.

The bore 77 of the cam-carrier 75 is toothed to provide an internal gear, and unless the hub-part 66 is expanded to wedge the cam-carrier fixedly thereto, the cam carrier is rotatable on the hub. The rear hub-part may be expanded, to fix the cam carrier to the hub, by means of a hand screw 78, which is screwed in a threaded hole 79 in the front hub-part 65 parallel with the axis of the hub, and which has a tapered end extending into the split of the rear hub-part, the walls of said split being provided with opposed arcuate grooves 80 which are engaged by the inner tapered end of the screw to wedge the split 85 apart and thus increase the external diameter of the hub part. The front end of the screw 78 protrudes and is provided with a knob 81 so that it may be grasped and the screw rotated to either expand the rear hub-part or to permit it to contract.

The carrier may be rotated on the hub when the rear hub-part is in its contracted state, by means of a pinion 82 mounted in a socket in the front hub-part and having its rear end 95 reduced and journaled in a bearing in the rear hub-part. The rear portion of the socket is open so that the pinion meshes with the internal gear of the cam-carrier. The front end of the pinion 82 protrudes and is pro- 100

vided with a hand knob 83 by means of which the pinion may be turned to rotate the cam-carrier. The pinion is prevented from accidental outward movement relative to the hub by means of the locking plate 84 slidably held on the end of the shaft 63 by a headed screw 85 which extends through a slot in said plate, the plate being thus slidably outwardly so that its arcuate end will fit against a circular shoulder on the knob 83. The plate is held fixed in its locking position by means of a binding screw 86 which extends through a hole in said plate and may be screwed into a threaded hole in the end of the shaft 63.

15 The cam member 87 is a ring having a cylindrical bore of differential diameter so as to be slipped into place on the cam carrier and on the front hub-part, as shown in Fig. 2, the exterior shoulder of the cam carrier and the interior shoulder of the cam member being rounded to facilitate the mounting of the cam ring.

The cam member is held against rotation relative to the carrier by means of a dowel pin 88 fixed to the carrier and engaging a hole 89 in the cam member. The cam member is also held against accidental lateral movement relative to the carrier by means of a ball-detent 90 spring mounted in a socket 91 in the carrier and engaging a socket 92 in the wall of the bore of the cam member.

The perimetral surface of the cam member 87 is the actuating surface of the cam structure and is engaged by the element which is 35 to receive its movement from the cam. Thus I have shown a lever 52 provided with a roller 57 which is in contact with the perimetral surface of the cam member 87.

The perimetral surface of the cam member 40 87 is given the eccentricity of contour requisite to impart the desired movement to the lever 52 or other element to be actuated.

The cam members are interchangeable and thus a cam member adapted to produce any 45 desired character of movement in the controlled element may be conveniently and quickly substituted.

It is obvious that my improved cam-driving mechanism is of extremely simple and compact construction and its adjustability and convenience makes the same highly useful and advantageous in cam-drives which are largely employed in many of the mechanical arts.

55 What I desire to claim is:—

1. In an actuating cam-structure, the combination of a hub arranged for mounting on a shaft, said hub being expandable, a cam-carrier ring rotatably mounted on said hub and 60 arranged to be fixed thereon by the expansion of the hub, and means for expanding the hub.

2. In an actuating cam-structure, the combination of a hub arranged for mounting on a shaft, said hub being expandable, a cam car-

rier ring rotatably mounted on said hub and arranged to be fixed thereon by the expansion of the hub, means for expanding the hub and a cam member detachably mounted on the carrier.

3. In an actuating cam-structure, the combination of a hub, a cam-carrier rotatable on said hub, said carrier being provided with an internal gear, a pinion carried by said hub and meshing with said gear whereby to rotate the carrier on the hub, and means for fixing the carrier relative to the hub.

4. In an actuating cam-structure, the combination of a hub, a cam-carrier rotatable on said hub, said hub being expandable to fix said carrier thereon, said carrier being provided with an internal gear, a pinion carried by said hub and meshing with said gear whereby to rotate the carrier on the hub, and means for expanding the hub.

5. In an actuating cam-structure, the combination with a shaft, of a hub comprising two parts and arranged to be fixed on the shaft, a cam-carrier mounted on and between said parts and rotatable relative thereto, 90 and means for fixing said carrier relative to said hub parts.

6. In an actuating cam-structure, the combination with a shaft, of a hub comprising two parts and arranged to be fixed on the said shaft, a cam-carrier mounted on and between said parts, one of said hub-parts being expandable to fix said carrier relative to the hub, and means for expanding said hub part.

7. In an actuating cam-structure, the combination with a shaft, of a hub comprising two parts and arranged to be fixed on the shaft, a cam-carrier mounted on and between said parts and rotatable relative thereto, 105 mechanism for rotating the carrier relative to the hub-parts, and means for locking the carrier in position relative to the hub-parts.

8. In an actuating cam-structure, the combination with a shaft, of a hub comprising two parts and arranged to be fixed on the said shaft, a cam-carrier mounted on and between said parts, one of said hub-parts being expandable to fix said carrier relative to the hub, mechanism for rotating the carrier relative to the hub parts, and means for fixing the carrier relative to the hub-parts.

9. In an actuating cam-structure, the combination of a hub, a cam-carrier rotatable on said hub, said carrier being provided with an internal gear, a pinion mounted on said hub and rotatable on an axis parallel to the axis of the hub, said pinion meshing with said internal gear whereby to rotate the carrier, and a cam ring detachably mounted on the carrier.

10. In an actuating cam-structure, the combination of a hub, a cam-carrier rotatable on said hub, said carrier being provided with an internal gear, a pinion mounted on said hub 120

and rotatable on an axis parallel to the axis of the hub, said pinion meshing with said internal gear whereby to rotate the carrier, means to lock the carrier relative to the hub, and a cam ring detachably mounted on the carrier.

5 Signed at Pittsburgh, Pa., this 9th day of August, 1928.

WILLIAM J. MILLER.
